WITNESS:

UNITED STATES PATENT OFFICE.

EMIL REICHENBAUM, OF FLINT, MICHIGAN.

FILING MACHINE.

1,412,217.

Specification of Letters Patent. Patented Apr. 11, 1922.

Application filed December 31, 1920. Serial No. 434,272.

To all whom it may concern:

Be it known that I, EMIL REICHENBAUM, a citizen of United States, residing at Flint, in the county of Genesee and State 5 of Michigan, have invented new and useful Improvements in Filing Machines, of which the following is a specification.

This invention relates to a power driven filing attachment for a drill press, and the 10 object is to provide in connection with a suitable frame work, provided with guides, a vertically reciprocating frame in which the file is mounted, and means for imparting movement to the frame.

15 A further object is to provide, in connection with the construction above specified, means for varying the strokes of the file holding device or frame.

A still further object is to provide a table 20 for holding the work being operated upon, and means for varying the angle of the table with reference to the file.

With the foregoing and other objects in view, the invention consists in the novel 25 construction, combination, and arrangement of parts hereinafter described and claimed.

In the accompanying drawings:

Figure 1 is a view of the machine in side elevation.

30 Figure 2 is a view in rear elevation.

Figure 3 is a horizontal section, on the line 3—3 of Figure 1.

Figure 4 is a perspective view of the file holding frame.

35 The main frame includes a base 10, an upright portion 12, and a head 14 provided with bearings 15 and 16 for mounting the horizontal shaft 17.

The head is provided with a bearing 18 40 mounting a short vertical shaft 20 having a tapered portion 21, this shaft carrying on the lower end thereof a beveled gear wheel 22.

Power is applied through the shaft 20, 45 and thence to the bevel gear wheel or pinion 22 meshing with a beveled pinion 23 on shaft 17, rotary movement being imparted to said shaft last named and to the disk 25, which in turn imparts movement to the element referred to below.

The disk is provided with a transverse

groove 26 in one face thereof, permitting of adjustment radially of the block 27 which has dovetail connection with the walls of the groove. The pitman 28 connected with 55 the block just referred to is also pivotally connected with a stud 29 projecting from the frame 30 operating in guides 31 on the vertical element of the frame of the machine. 60

The frame 30 includes vertical elements 31 and the laterally extending arms 32 and 33, each being provided with a socket portion 34 for receiving one end of the file 35. Thumb screws 36 serve to retain the file in 65 the socket members. In view of the adjustable mounting of the block 25 with reference to the disk 25, the length of the stroke of the frame or file holding device 30 may be varied as desired. 70

A table 37 is adjustably mounted on an upright 38 secured to the base 10, in the manner illustrated. The adjustable connection is effected by means of the screw 40 passing through ears 41 on the table 37, and 75 also passing through the upper end of the vertical element of the stand.

The various adjustments permit of the engagement of the work by the tool in the manner desired for producing a given result, 80 and also permit of the use of a considerable portion of the file.

What is claimed is:

In a device of the class described, a main frame, provided with guideways, a file holding frame movable in the guideways, a shaft and means for driving the latter and means for imparting movement to the second named frame, from said shaft, the file holding frame comprising a plate member the 90 edge portions of which engage the guideways, spaced laterally extending arms carried by the plate and each provided with a socket portion for receiving the opposite ends of a file, devices for clamping 95 the file in the sockets, a stud projecting from the plate in a direction opposite to that in which the arms extend and having connection with said means for imparting movement. 100

In testimony whereof I affix my signature.
EMIL REICHENBAUM.
